UNITED STATES PATENT OFFICE.

GOTTFRIED JOHNSON, OF CHICAGO, ILLINOIS.

TRICYCLE.

SPECIFICATION forming part of Letters Patent No. 408,624, dated August 6, 1889.

Application filed June 17, 1889. Serial No. 314,637. (No model.)

To all whom it may concern:

Be it known that I, GOTTFRIED JOHNSON, a subject of the King of Sweden, residing at Chicago, in the county of Cook and State of Illinois, have invented certain new and useful Improvements in Tricycles, of which the following is a specification.

My invention relates to improvements in tricycles; and it consists in certain peculiarities of the construction and arrangement of the same, as will be hereinafter more fully set forth and specifically claimed.

In order to enable others skilled in the art to which my invention pertains to make and use the same, I will now proceed to describe it, referring to the accompanying drawings, in which—

Figure 1 is a view of my machine in elevation. Fig. 2 is a longitudinal sectional view taken on line x x of Fig. 1. Fig. 3 is a vertical sectional view of the steering-shaft. Fig. 4 is an end view of the drum, and Fig. 5 is a side view of the two drums and the endless chain in position.

Similar letters refer to like parts throughout the different views of the drawings.

A represents the main frame, upon which is mounted in the usual way or in any suitable manner one or more saddles or seats a a' , which seats are secured to the frame A by means of braces a^2 , or otherwise, as may be desired. The upper braces are loosely secured at one end to a bracket b , and are loosely provided at the other end with a collar b' , surrounding the seat-supporting standard b^2 , which standard passes through said collar and is secured therein by means of a set-screw. Between the collars and the lower braces and around the lower portion of the standard b^2 , I place a spiral spring b^3 , which prevents jolting when the machine passes over rough places.

In front of the seat a , at a suitable point, is loosely secured in the frame A at its lower end a steering-shaft c , having at its upper end the usual crank-handle c and brake-grip d^5 . The shaft c is further supported and held in a vertical position by the bracket b , through which it passes. Between the upper part of the bracket b and the frame A on the shaft c , I provide two arms c^2 , which extend

horizontally from the shaft c and on each side thereof. To the end of each arm is secured a cord or chain c^3 , which passes over suitable pulleys c^4 and under similar pulleys c^5 , and connects at their other ends with like arms c^2 on the main steering-shaft. The pulleys c^4 and c^5 are suitably secured to the frame A at the proper points.

In front of the seat a' , and secured to the front end of the frame A , is the main steering-shaft A' , having at its upper end the usual handle c' , and formed at its lower end with a fork n , carrying the steering-wheel B , journaled therein, as shown in Fig. 1 of the drawings.

The rear end of the frame A is loosely secured in the forked piece E at a suitable distance from the upper end thereof, as at E^2 , as will be more clearly seen by reference to Figs. 1 and 2 of the drawings. The piece E is preferably formed, as shown in Fig. 1, with its forked ends projecting downward and having journaled therein the axle or shaft d' , upon which is mounted the wheel C , drum e , treadle-arms f f' , and pendant f^2 . At a short distance in front of the bearing of the rear end of the frame A , as seen at E^2 , and near the curve or bend in the piece E , I journal the axle or shaft d^2 , upon which shaft is mounted a drum e' , similar in construction to the drum e , but preferably larger in circumference. The ratchet-wheel e^3 and pawl-bearing arms or levers g g' are also journaled on the shaft d^2 , as is apparent. At the rear end of the piece E , I loosely and vertically journal the forked shank d near its upper end, which shank has at the lower ends of its fork suitable bearings in which is journaled the axle of the wheel D , as is clearly seen in Fig. 1, and has secured to one side of the fork a step-piece d^4 , to assist the rider in mounting the machine.

In Fig. 3 I have shown a detailed construction of my main steering-shaft A' , in which is a vertical rod or bar having at its upper end the ordinary handle c' and brake-grip d^5 , which grip is connected to and operates the brake m through the rods m' and lever m^2 , the lever being fulcrumed to the enlarged part n^6 of the shaft A' , as at m^3 , and the brake m pivoted to the shank of the fork n , as at n' , as is seen in Fig. 1 of the drawings. To the

front end of the frame A is rigidly secured a sleeve n^2 , which fits around the enlarged part of shaft A', which enlarged part is hollow and is provided therein with a plate n^8 , having a square hole n^4 through said plate, into which hole the rectangular upper part of shank o' of the fork n fits, and is allowed to move upward when the wheel B passes over a stone or other object. In the upper end of the shank o' is secured a pin n^7 , which projects slightly on each side of the shank and prevents it being drawn out. The enlarged part n^6 may be made integral with the shaft A', or it may be a separate piece, as shown in Fig. 3. Within the hollow piece n^6 , I provide a suitable spiral spring o, which encircles the shank o' and rests between the projecting plate n^8 and shoulders o^2 , formed on the shank o', as seen. The arms c^2 are rigidly secured to the bottom of the piece n^6 and are provided near their outer ends with suitable means for connecting the cords or chains c^3 when desired.

The shank o' is of rectangular form and fits into a similarly-formed opening in the piece n^6 , as at n^4 , which construction permits the shank to move upward when passing over stones, &c., and yet can be turned to the right or left when desired.

In Fig. 4 I have shown an end view of one of the drums provided at suitable points on its periphery with tapering or funnel-shaped holes p, into which the projections on the endless chain engage, as shown in Fig. 5.

The endless chain F is formed of short pieces r and r', connected together by pins r^2 . The pieces r are formed with each end bifurcated and provided with holes, into which the pins r^2 are inserted through holes in each end of the pieces r', which are provided on one side, about the center of the piece, with a tapering or wedge-shaped lug or projection r^3 , which projection engages with the holes p in the drums e e', as is clearly seen and will be readily understood.

It is apparent that by using the wedge-shaped lugs on the chain, in connection with the tapering holes in the drums, the pins never fail to engage said holes, and that the greater the strain the more secure is the engagement; yet after having passed over the drum they are released without hindrance. While I prefer to use the chain formed as above described with the drums, yet it is evident that I may substitute therefor the ordinary sprocket-wheel and chain.

On the shaft d', and between the forks of the bearing E, I rigidly secure to the said shaft the wheel C, having rigid therewith and on one side of the wheel the drum e, having the tapering holes p, as before described. Passing over this pulley or drum and engaging with the drum e', which is mounted on the shaft d', is the endless chain F.

On each side of wheel C and outside of the forks of the piece E, I loosely journal the treadle-arms f f', having pivoted at each end thereof foot-rests s s, which are kept level by

means of the connecting-rods s' s', connected at one end to the pendant f², which is secured firmly to the piece E. On the inner side of the treadle-arms I provide two springs t t', one end of which is secured to the pendant f² and the other end to the arms f f', as seen by the dotted lines in Fig. 1.

To the arms f f', at a suitable place, are loosely secured the lever-operating rods i i', which are adjustably secured to the pawl-carrying levers g g'. The said levers are journaled, as shown, on the shaft d², and have the spring-actuated pawls h h', which engage with the ratchet-wheel e², mounted on the shaft d².

The springs t t' are removably connected to the pendant f² and arms f f', so that when one person only rides the machine one of the springs may be removed and the other one will compensate for the absence of the other rider.

The operation of my machine is evident. The wheel D may be turned at right angles with the wheel C, when the vehicle will stand erect. The foot of the rider may then be placed in the step d⁴ and the mount easily made. After the rider or riders are mounted and have placed their feet on the pedals s s', by throwing their weight on first one foot and then on the other, the wheels are set in motion. The levers g g', being raised and lowered and engaging with the ratchet-wheels by means of their pawls, will rotate the chain-bearing drums and keep the wheels in motion. To steer the machine it is only necessary to turn either of the shafts c or A' to the right or left, as is clear.

Near the front end of the main frame A, I secure thereto a forked piece Q, having on the inside of each prong of the fork a small roller u. The fork thus provided with rollers straddles the rim of the wheel C and prevents any lateral strain thereon.

Having thus fully described my invention, what I claim as new, and desire to secure by Letters Patent, is—

1. In a tricycle, the combination of three wheels placed one before the other, a main frame connecting said wheels, the steering-shafts, the drums having a connecting-chain provided with lugs, ratchet-wheels, the pawl-bearing levers, and the connecting-rods, all arranged and operating substantially as and for the purpose set forth.

2. In a tricycle, the combination of the main frame A, forked piece E, the drums e e', chain F, ratchet e³, pawls h h, levers g g', connecting-rods i i', treadle-arms f f', having pedals s s, steering-shaft A', and wheels B C D, substantially as shown and described, and for the purpose set forth.

3. In a tricycle, the steering-shaft A', having the handle c', brake m, lever m², rod m', grip d⁵, and a fork n at its lower end, in combination with the wheel B, and the frame A, having connected thereto the wheels C D, substantially as and for the purpose set forth.

4. In a tricycle, the steering-shaft A', hav-

ing the handle c' , brake m , lever m^2 , rod m' , grip d^5 , the hollow piece n^6 , provided with plate n^8 , having a square hole n^4 , the shank o' , having shoulders o^2 , fork n , and the spring o , encircling the shank o' and resting between the plate n^8 and shoulders o^2 within the hollow piece n^6 , in combination with the wheel-bearing frame A, having sleeve n^2 , and the wheel B, all constructed, arranged, and operating substantially as shown and described, and for the purpose set forth.

5. In a tricycle, the steering-shaft A', having handle c' , brake m , lever m^2 , rod m' , grip d^5 , the hollow piece n^6 , having hole n^4 in plate n^8 and arms c^2 , the compensating spring o , encircling the shank o' , having shoulders o^2 , and fork n , carrying wheel B, in combination with the frame A, having the sleeve n^2 , wheels

C D, pulleys $c^4 c^5$, chains c^8 , connected at one end to the arms c^2 and at the other end to arms c^2 on standard c, the standard c, having handle c' , brake, grip, and connecting-rods, substantially as shown and described, and for the purpose set forth.

6. In a tricycle, the combination of the seat a' , standard b^2 , collar b' , spring b^3 , brace-bearings $a^2 a^2$, the frame A, having bracket-arms b , and wheels B C D, substantially as shown and described, and for the purpose set forth.

In witness whereof I have hereunto set my hand and affixed my seal this 12th day of June, 1889.

GOTTFRIED JOHNSON. [L. S.]
In presence of—

FRANK T. ROBINSON,
J. A. PIATT.
